Primary Examiner — Catherine Tuttle(74) Attorney, Agent, or Firm — Porzio, Bromberg & Newman, P.C.(57) CLAIM

I claim, the ornamental design for a perfume bottle, as shown and described.

DESCRIPTION

The patent or application file contains a least one photograph executed in color. Copies of this patent or patent application publication with color drawings will be provided by the Office upon request and payment of the necessary fee.

FIG. 1 is a perspective view of a perfume bottle in an open state, showing my new design; and,

FIG. 2 is a front view of the perfume bottle in a closed state.

1 Claim, 2 Drawing Sheets
